ATTORNEY

UNITED STATES PATENT OFFICE

FREDERICK JOHN HIRSCHMANN, OF SAN LEANDRO, CALIFORNIA

FREIGHT-CAR DOOR

Application filed November 24, 1926. Serial No. 150,508.

The present invention relates to improvements in freight car doors, and its particular object is to provide improved supporting and locking means for a freight car door. It is particularly proposed in this connection to provide a sliding support for the door of the character described that allows of easy operation of the door, prevents binding action, and allows the door to be easily taken off for replacement by a new door. It is further proposed to provide improved locking means adapted to lock the door in any one of a number of different positions. It is further proposed to provide locking means that will hold the door firmly in place and allow the door to be firmly pressed upon the door frame. It is a further object of the invention to provide a locking means that may be easily applied and easily released. Further objects and advantages of my invention will appear as the specification proceeds.

The preferred form of my invention is illustrated in the accompanying drawing in which—

Figure 1 shows an elevation of my door as attached to the side of a railroad car,

Figure 2 a vertical section taken along line 2—2 of Figure 1,

Figure 3 a vertical section taken along line 3—3 of Figure 1,

Figure 4 a vertical section taken along line 4—4 of Figure 1, and

Figure 5 a detail view of a supporting element as seen from line 5—5 of Figure 1.

While I have shown only the preferred form of the invention, I wish to have it understood that various changes or modifications may be made within the scope of the claims hereto attached without departing from the spirit of the invention.

The side wall 1 of a railroad car is formed with a door opening 2 and has a rod 3 supported above the door opening. The latter rod is formed at one end with a ring 4 adapted to be slipped over an elbow-shaped bolt 6 fastened to the side of the railroad car by means of a nut 7 and a cotter pin 8. The elbow in the bolt allows the rod to be swung sideway or downwardly or thru any intervening plane, thereby imparting a universal

motion to the rod. The free end of the latter is held in a bracket 9 entering into the same thru the slot 11 and held against removal by a bolt 12. The rod is of sufficient length to allow the door 13 to slide from an active position in which it closes the door opening to an inactive position in which it clears the door opening. The door 13 is formed with a hood 14 extending thruout the length thereof and adapted to ride on the rod 3, the hood being provided, below the rod, with a plurality of rollers 16 which prevent binding of the door on its runway. It will be noted that when it is desired to replace a door by another one, it is only necessary to pull out the bolt 12 from the bracket 9 and to swing the rod 3 outwardly and downwardly which will cause the door to roll off by its own weight.

Below the bottom edge of the door, there is supported, in bearings 17, a shaft 18 which has a number of arms 19 fastened thereto and is provided with a handle 21 by means of which it may be manipulated. The door itself is formed in its lower portion with a plurality of vertically extending grooves or depressions 22 corresponding in their spacing to the spacing of the arms 19 and allowing the latter to rest therein. It will be noted that by manipulation of the handle 21, the arms may be pressed into the grooves 22 if the door is in the proper position and the arms may be made to press upon the door so as to hold the same close to the door frame while holding the door against sliding motion. In the act of pressing the arms upon the door, the handle passes over a member 23, the handle being formed with a slot 24 for this purpose, and also over a pawl 26 which latter is shaped and weighted to rise behind the handle and to prevent its return. For releasing the handle, the pawl 26 is manually operated. It will be noted that the distribution of the arms 19 allows the door to be locked in any one of a number of positions since the third arm 19 may be used to bear upon either the first or the second or the third groove 22, while when the door is open altogether, the fourth arm 19 becomes active.

The lower section of the door may be held from swinging outwardly too far by means

of a chain 27 fastened to a ring 28 slidable on the shaft 18. Above the rod 3, there is provided an angle iron 29 and a bar 31 rises from the hood 14 and bears against the vertical flange of the angle iron 29 when the door is suspended vertically.

The manner of using my invention will be readily understood from the foregoing description. The door rides easily on the rod 3 due to the length of the supporting space 10 of the hood and due to the interposition of the rollers. The door may be removed altogether without difficulty by withdrawing the bolt 12 from the bracket 9 and allowing the rod 3 to swing forward and downward as indicated in dotted lines in Figure 1, and a new door may be placed on the rod in a similar manner. To unlock the door, it is only necessary to release the pawl 26 and to pull the handle 21 downward which frees the door of 20 the arms 22 and allows the same to slide back and forth. The door may be easily locked in either closed, or half-open, or open position by forcing the arms 19 into the depressions or grooves 22 and the handle is locked against reversal by the pawl 26. Opening and closing of the door may be effected without any trouble since at no place can there be any binding of the door. The door cannot be locked in closed position from within the 30 car so that the presence of an unauthorized person within the car will be readily noticed from the caboose because the door will swing unless locked from the outside. The advantage of one continuous hinge or hood is apparent since in an arrangement with several hinges it frequently occurs that the hinges become disaligned which makes it difficult to operate the door.

It will be seen that my closure is absolutely 40 watertight due to the engagement of the bar 31 with the angle iron on top and the pressure of the arms 19 at the bottom and that this manner of securing the door prevents 45 the same from warping. In order to insure a tight fit of the door against the wall of the car, the member 23 may be adjustably secured in the wall by means of screws 32 passing through flanges 33 of the said member 50 into the wall of the car, while shims may be interposed between the wall and the flanges for positioning the member 23.

I claim:

1. In combination, a slidably suspended 55 freight car door and means movable transversely to the plane of the door adapted to bear thereon for holding the same in place, against lateral movement, both to open and closed positions.

60 2. In combination, a slidably suspended freight car door and an arm pivoted to swing in a plane transverse to that of the door adapted to bear thereon for holding the same in place, against both opening and closing lateral movement.

3. In combination, a slidably suspended freight car door, a shaft mounted parallel to the lower edge thereof, arms on the shaft adapted to bear on the door for holding the same in place against both opening and closing lateral movement, a handle on the shaft 76 for manipulating the same and means for locking the handle in place, thereby holding the door in a plurality of partly opened or in closed positions.

4. In combination, a slidably suspended freight car door having a plurality of depressions formed in the lower portion thereof, a shaft mounted parallel to the lower edge of the door and an arm extending from the shaft adapted to be pressed into any one of the depressions for holding the door against sliding movement, thereby holding the door in an adjusted opening or in its closed position against lateral movement in both directions.

5. In combination with a freight car door, means for slidably suspending said door, and means movable transversely to the plane of the door adapted to bear thereon for holding the same in place, said suspending means comprising a rod above the door opening hinged at one end with freedom of universal motion, and detachably secured at the other end with means on the door slidable on said rod.

6. In combination with a freight car door having a supporting means therefor, said door having a plurality of depressions formed in the lower portion thereof, a shaft mounted parallel to the lower edge of the door and an arm extending from the shaft adapted to be pressed into any one of the depressions for holding the door against sliding movement; said supporting means comprising a rod secured above the door opening, a hood secured to the door and extending throughout the length thereof slidable on the rod, and rollers supported on said hood below the rod.

7. In combination, a slidably suspended door having a depression in the face thereof, and a rocking arm for engaging the depression for urging the door inwardly.

8. In combination, a slidably suspended door having spaced apart depressions in the face thereof, rocking arms in complementarily spaced relation to the depressions for cooperation therewith, and means for securing the arms within the depressions.

9. In combination, a slidably suspended door having spaced apart depressions in the face thereof, a pivoted bar, arms carried by the pivoted bar in spaced relation complementarily to the depressions for cooperation therewith in forcing the door inwardly and means for securing the door in its inwardly forced position.

10. In combination with a freight car door, having spaced apart depressions in the face thereof, means for slidably support-

ing the door, a rotatable shaft positioned below and adjacent the lower edge of the door, securing arms for cooperation with the depressions carried by the shaft and in complementarily spaced relation with the depressions, an operating handle affixed to one end of the shaft and means passing through the handle for locking the arms within the depressions.

10 In testimony whereof I affix my signature.
FREDERICK JOHN HIRSCHMANN.
